(57) **CLAIM**

The ornamental design for a display screen with graphical user interface, as shown and described.

DESCRIPTION

FIG. 1 is a front view of a display screen with graphical user interface showing a first embodiment of our new design; FIG. 2 is a partial enlarged view taken along line 2-2 in FIG. 1 provided for clarity of illustration; FIG. 3 is a partial enlarged view taken along line 3-3 in FIG. 1 provided for clarity of illustration; FIG. 4 is a partial enlarged view taken along line 4-4 in FIG. 1 provided for clarity of illustration; FIG. 5 is a front view of a display screen with graphical user interface showing a second embodiment of our new design; FIG. 6 is a partial enlarged view taken along line 6-6 in FIG. 5 provided for clarity of illustration; FIG. 7 is a partial enlarged view taken along line 7-7 in FIG. 5 provided for clarity of illustration; FIG. 8 is a partial enlarged view taken along line 8-8 in FIG. 5 provided for clarity of illustration; FIG. 9 is a front view of a display screen with graphical user interface showing a third embodiment of our new design; FIG. 10 is a partial enlarged view taken along line 10-10 in FIG. 9 provided for clarity of illustration; FIG. 11 is a partial enlarged view taken along line 11-11 in FIG. 9 provided for clarity of illustration; FIG. 12 is a partial enlarged view taken along line 12-12 in FIG. 9 provided for clarity of illustration; FIG. 13 is a partial enlarged view taken along line 13-13 in FIG. 9 provided for clarity of illustration; FIG. 14 is a front view of a display screen with graphical user interface showing a fourth embodiment of our new design;

(Continued)

FIG. 15 is a partial enlarged view taken along line 15-15 in FIG. 14 provided for clarity of illustration; FIG. 16 is a partial enlarged view taken along line 16-16 in FIG. 14 provided for clarity of illustration; and, FIG. 17 is a partial enlarged view taken along line 17-17 in FIG. 14 provided for clarity of illustration. The outermost evenly-spaced broken lines showing a display screen, as well as those evenly-spaced broken lines showing portions of the graphical user interface, are included for the purpose of illustrating portions of the article; the dot-dash broken lines define the boundary of the claimed design and form no part thereof; the dot-dot-dash broken lines indicate limits of enlarged views; all broken lines form no part of the claimed design. Additionally, it is understood that all portions of the graphical user interface outside the solid line regions form no part of the claimed design.
